UNITED STATES PATENT OFFICE.

JABEZ BURNS, OF BROOKLYN, NEW YORK.

MIXING-MACHINE.

SPECIFICATION forming part of Letters Patent No. 279,328, dated June 12, 1883.

Application filed February 2, 1883. (No model.)

To all whom it may concern:

Be it known that I, JABEZ BURNS, a citizen of the United States, residing at Brooklyn, in the county of Kings and State of New York, 5 have invented new and useful Improvements in Mixing-Machines, of which the following is a specification.

This invention relates to machines for mixing tea, glazing coffee, or other similar pur- 10 poses; and it consists in the novel construc- tion and arrangement of parts hereinafter de- scribed, and illustrated in the accompanying drawings, in which—

Figure 1 represents a vertical longitudinal 15 section. Fig. 2 is an end view. Fig. 3 is a cross-section on the line xx , Fig. 1. Fig. 4 is a detail view.

Similar letters indicate corresponding parts.

The letter A designates two standards form- 20 ing the bearings for a shaft, B, which is pro- vided with pulleys, or otherwise arranged to receive a revolving motion. On this shaft is mounted a mixing-drum, which is divided transversely, and at about its mid-length, into 25 two sections, C C', one of which is fixed to the shaft, while the other is keyed thereto by a feather or spline, o, so that this section is adapted to slide on the shaft, and at the same time share its motion. Those portions of the 30 drum-sections C C' engaging the shaft B consist of spiders or skeleton heads D D', and with the fixed section C is combined a hopper, E, which serves to feed the material to the drum through the head D, such hopper being 35 secured to one of the standards A. If desired, however, either drum-section may be provided with a feed-opening, closed by a suitable cover, and in that case the heads D D' may be solid.

40 The letter G designates a revolving sleeve, whereby the sliding drum-section C' is locked against the fixed section. This sleeve is fitted on the shaft B and connected to the sliding drum-section C', by means of a coupling- 45 piece, H, which is secured to the head D', and engages a circumferential groove, f, in the sleeve. Said sleeve, moreover, is provided with a spiral slot, i, whereby it engages a guide-pin, k, on the shaft B, so that when the 50 sleeve is turned in one direction it slides out- ward on the shaft, carrying with it the slid- ing drum-section C', whereby an opening is created between the drum-sections for the dis-

charge of material from the drum, while when the sleeve is turned in the other direction it 55 slides to an inner position, thereby forcing the sliding drum-section back against the fixed section, and holding it in that position. The sleeve G is provided with a hand-wheel, G', for turning it, and in order to prevent the ac- 60 cidental displacement of the sliding drum-section the outer terminal of the spiral slot i is made straight transversely to the shaft. Both drum-sections C C' are inclined downwardly from the outer to the inner end, as shown in 65 Fig. 1, and the material thus having a tendency to move toward the center or division line of the drum, its discharge is facilitated or hastened.

If desired, both drum-sections C C' may be 70 provided with inclined ribs to throw the ma- terial toward the ends of the drum, and the locking-sleeve G, moreover, may carry the guide-pin k, in which case the shaft is pro- vided with a groove, which may be partly 75 spiral and partly longitudinal to the shaft.

What I claim as new, and desire to secure by Letters Patent, is—

1. The combination, substantially as here- 80 inbefore set forth, with the revolving shaft, of the mixing-drum divided into two sections, one fixed and the other adapted to slide on the shaft, and a device for locking the sliding drum-section against the fixed section.

2. The combination, substantially as here- 85 inbefore set forth, of the mixing-drum divided into two sections, with the revolving shaft provided with a guide-pin, and having one section fixed to the shaft and the other adapted to slide thereon, and with the locking-sleeve 90 connected to the sliding drum-section, and pro- vided with a spiral slot whereby it engages the guide-pin on the shaft, for the purpose specified.

3. The combination, substantially as here- 95 inbefore set forth, of the mixing-drum divided into two sections, both inclined downwardly from the outer to the inner end, with the re- volving shaft and locking device.

In testimony whereof I have hereunto set 100 my hand in the presence of two subscribing witnesses.

JABEZ BURNS.
